UNITED STATES PATENT OFFICE.

STEPHEN NICHOLSON AND SAMUEL M. NICHOLSON, OF PROVIDENCE, RHODE ISLAND, ADMINISTRATORS OF WILLIAM T. NICHOLSON, DECEASED.

DESIGN FOR A FILE-HANDLE.

SPECIFICATION forming part of Design No. 25,410, dated April 21, 1896.

Application filed April 8, 1895. Serial No. 545,016. Term of patent 14 years.

To all whom it may concern:

Be it known that WILLIAM THOMAS NICHOLSON, deceased, a citizen of the United States, formerly residing in the city of Providence, county of Providence, and State of Rhode Island, did invent and produce a new and original Design for File-Handles, of which the following is a specification, reference being had to the accompanying drawing, forming part thereof.

The drawing is a representation of the handle showing the design in solid lines and part of a file in broken lines.

The leading feature of the design consists in the outline of the handle and ferrule formed of continuous curved lines uniting where the file is inserted in a semispherical end and at the opposite end in a semioval point.

The form of the handle is designed to present a smooth round shape that will conform to the hand, rest firmly against the ball in the hollow of the hand, and a finger, usually the first finger, rests on the semispherical ferrule end with the point of the finger resting on the file, thereby securing a firmer hold on the handle and a better control of the file.

In the drawing the part 1 below the line *aa* is of oval shape. The part 2, between the lines *aa* and *bb*, is a cylindrical bulb, uniting with the oval at the line *aa* and with the neck 3 at the line *bb*. The gradually-contracting neck 3 gradually increases in diameter until it meets the ferrule 4, and then continues to the line *c*, where the curved line of the neck intersects the semispherical part 5 of the ferrule, which has an opening for the reception of the file-shank.

All parts of the handle are round in cross-section.

What is claimed is—

The design for the file-handle as herein shown and described.

In witness whereof we have hereunto set our hands.

STEPHEN NICHOLSON,
SAM'L M. NICHOLSON,
Administrators of estate W. T. Nicholson.
